UNITED STATES PATENT OFFICE.

JAMES W. PENNEWILL AND MOSE R. BUCHANAN, OF SILVER CITY, NEW MEXICO.

ELECTRICALLY-OPERATED TIME-SWITCH.

1,138,406.

Specification of Letters Patent.

Patented May 4, 1915.

Application filed July 23, 1913. Serial No. 789,654.

To all whom it may concern:

Be it known that we, JAMES W. PENNEWILL and MOSE R. BUCHANAN, citizens of the United States, and residents of Silver City, in the county of Grant and State of New Mexico, have invented a new and Improved Electrically-Operated Time-Switch, of which the following is a full, clear, and exact description.

10 This invention relates to an electrically-operated time switch especially adapted for lighting circuits whereby the lamps can remain lighted only for predetermined intervals so that there will not be a waste of current by the lights being kept burning when they are not needed, such a switch being especially useful in refrigerating or cold storage rooms where the employees are likely to leave the lamps in circuit negligently 15 when they pass out of the room after having performed the duty that necessitated their entrance. This not only prevents an unnecessary waste of current but relieves the refrigerating plant from undue work to 20 keep the temperature down to normal against the heat generated by the lamps.

The invention has for its general objects to improve and simplify the construction and operation of devices of the character 30 referred to so as to be reliable and efficient in use, comparatively inexpensive to manufacture and install and so designed that a minimum of current is required to operate the switch.

35 Another object of the invention is the provision of a motor-actuated switch including novel means for driving the movable contact of the switch by the motor and yet providing for the closing of the switch by hand, 40 the opening and closing of the switch being effected on the quick-acting principle so that destructive sparking is overcome.

With such objects in view, and others as will appear as the description proceeds, the 45 invention comprises various novel features of construction and arrangement of parts which will be more fully described herein-after and set forth with particularity in the claims appended hereto.

50 In the accompanying drawing, which illustrates one embodiment of the invention, and wherein similar reference characters are employed to designate corresponding parts throughout the several views, Figure 1 is a 55 diagrammatic view of the motor-operated switch, the switch proper being shown in sec-

tion; and Fig. 2 is a front view of the switch proper.

Referring to the drawing, A designates a switch of the quick-acting type, B a motor therefor, and C the power transmitting means between the rotating part of the motor and the movable element of the switch.

The switch A comprises a supporting plate 1 on which are mounted concentric contacts 2 and 3 which are incomplete circles, there being segments 4 and 5 of insulation which serve to complete the circle. A movable contact 6 rides over the fixed contacts 2 and 3 and insulation segments 4 and 5, such contact 6 serving to electrically connect the contacts 2 and 3 and thus complete the lighting circuit. This lighting circuit includes a suitable source of current and the wires 7 and 8 forming one side of the circuit are connected with the segments 2 and 3, respectively, the other side of the circuit being formed by the wire 9. As shown in Fig. 1, any suitable arrangement of lamps 10 may be connected with the wires 7 and 9, so as to be connected in circuit as long as the bridging contact 6 engages the contacts 2 and 3. The bridging contact 6 is hingedly connected at 11 with an arm 12 that turns on a shaft 13 concentric within the circular contacts 2 and 3, and a spring 14 is connected with the outer end of the arm 12 and also with the contact 6, so that the arm 12 can be moved while the bridging contact 6 is temporarily restrained, especially when the latter is about to leave or move into engagement with the contacts 2 and 3, whereby the spring 14 is placed under tension to effect a quick movement of the contact 6 when the latter is released, so that sparking will not occur at the ends of the contacts 2 and 3 during the passage of the contact 6. This restraining and releasing of the contact 6 is effected by stops 15 and 16 located respectively at the leaving and approaching ends 17 and 18 of the contacts 2 and 3. The contact 6 projects outwardly beyond the contact 3 so as to strike the stop 15 or 16 as the arm 12 moves in a clockwise direction, Fig.

2. When the arm 12 reaches a certain position the tip 19 of the contact 6 passes under the restraining stop and quickly snaps off the leaving ends of the contacts 2 and 3 when the stop 15 is considered, or quickly passes onto the approach ends of the contacts 2 and 3 when the stop 16 is considered. The shaft 13 is motor-driven during the

time the bridging contact 6 is in engagement with the contacts 2 and 3, but the arm 12 must be manually operated to close the switch by bringing the contact 6 into engagement with the ends 18 of the contacts 2 and 3. To permit the arm 12 to be manually turned to close the switch while the shaft 13 remains stationary a clutch device is employed between the arm 12 and shaft 13, such device consisting of spring washers 20, Fig. 1, which yieldingly engage opposite sides of the arm 12, such washers being mounted on the shaft 13. The turning of the arm 12 is effected by a handle or 15 equivalent device 21.

The motor B which drives the contact-carrying arm 12 continuously during the time the lamps 10 are lighted consists of a core 22 having its poles 23 and 24 disposed at opposite sides of an aluminum disk 26 which is fastened to a rotatable shaft 27, such shaft being connected by a worm gearing 28 with a shaft 29 that is in turn connected by a cog gearing 30 to the shaft 13. 20 Wound on the pole 23 is a potential coil 31 connected by wires 32 and 33 with the wires 7 and 9, respectively, and in the wire 7 is a current coil 34 which is wound on the other pole of the motor core 22. Current 25 passing through the coils produces magnetic fluxes which generate in the aluminum disk current that in turn sets up a magneto-motive force which reacts on the magnetic field due to the poles and causes the disk 26 to 30 turn, and this turning continues as long as current is flowing through the circuit to keep the lamps 10 lighted. The interval of illumination depends upon the effective length of the contacts 2 and 3 or the speed 35 of the motor and the speed ratio of the transmission means C between the motor and the contact-carrying arm 12. Any of these factors may be varied to keep the lights burning for any desired period of time. When 40 the lights go out and the person in the cold storage room is not through with the task he is to perform he must again close the switch by manipulating the arm 12 in a direction to carry the contact over the insulating segments 4 and 5 and into engagement 45 with the contacts 2 and 3. Of course, during the time the switch is opened the motor is out of circuit so that there is no consumption of current.

50 From the foregoing description taken in connection with the accompanying drawings, the advantages of the construction and method of operation will be readily understood by those skilled in the art to which

the invention appertains, and while we have 60 described the principle of operation, together with the apparatus which we now consider to be the best embodiment thereof, we desire to have it understood that the apparatus shown is merely illustrative, and 65 that such changes may be made when desired as are within the scope of the appended claims.

Having thus described our invention we claim as new and desire to secure by Letters 70 Patent:

1. A switch comprising fixed contacts, an element movable with respect to the said contacts, a bridging contact movable along the fixed contacts, a hinged connection between the contact and element whereby the contact is moved by the latter, said movable contact extending across the fixed contact with a free end projecting beyond the latter, stops being arranged adjacent the ends of the fixed contacts and located in the path of the movement of the free end of the movable contact, whereby the latter wipes against the stops to retard the movement of the movable contact while the said element moves, and a spring connected with the movable contact and element and adapted to be placed under tension while the movable contact is in engagement with a stop for causing the movable contact to pass quickly off the fixed contacts at one end or on the contacts at the opposite ends.

2. In a switch device of the class described, the combination of a shaft, an arm thereon, a clutch between the arm and shaft for permitting the arm to be moved while the shaft is stationary, a movable contact mounted on the arm, fixed contact means over which the movable contact travels, stop devices adjacent the ends of the movable contact means for momentarily arresting the movable contact while the arm continuously moves, and a spring connected with the arm and movable contact and arranged to be placed under tension by the momentary arresting of the movable contact for causing the latter to move quickly on or off the fixed contact means as the movable contact passes the said stop devices.

In testimony whereof we have signed our names to this specification in the presence of two subscribing witnesses.

JAMES W. PENNEWILL.
MOSE R. BUCHANAN.
